[57] CLAIM

The ornamental design for a display holder for a shelf, as shown and described.

DESCRIPTION

FIG. 1 is a front elevational view of a display holder for a shelf, showing my new design;
FIG. 2 is a side elevational view, the opposite side being a mirror thereof;
FIG. 3 is a top plan view;
FIG. 4 is a bottom plan view;
FIG. 5 is a rear elevational view;
FIG. 6 is a cross-sectional view, taken along line 6—6 in FIG. 3; and,
FIG. 7 is a perspective view thereof, the broken lines are for environmental purposes only and form no part of the claimed design.

FIG. 1**FIG. 2****FIG. 3****FIG. 4****FIG. 5****FIG. 6****FIG. 7**
